UNITED STATES PATENT OFFICE.

J. WRIGHT, OF ST. LOUIS, MISSOURI.

IMPROVEMENT IN BOLTING FLOUR, &c.

Specification forming part of Letters Patent No. 41,737, dated February 23, 1864.

To all whom it may concern:

Be it known that I, J. WRIGHT, of St. Louis, in the county of St. Louis and State of Missouri, have invented a new and Improved Bolting Apparatus or Device for Bolting Flour, Dusting Bran, and Like Purposes; and I do hereby declare that the following is a full, clear, and exact description of the same, reference being had to the accompanying drawings, making a part of this specification, in which—

Figure 1 is a side sectional view of my invention taken in the line xx , Fig. 2; Fig. 2, a horizontal section of the same taken in the line yy , Fig. 1; Fig. 3, a detached perspective view of the means employed for giving a shake motion to the bolt.

Similar letters of reference indicate corresponding parts in the several figures.

This invention consists in having one or more spiral screens and a spiral chute attached to a vertical rotating shaft and inclosed by a suitable case, whereby the flour, bran, or other substance to be bolted or screened will be allowed to pass down and over the screen and chute as the latter revolve, and be bolted or screened in the most thorough manner.

The invention also consists in using, in connection with the spiral screen and chute aforesaid a hopper, which is also attached to the screen-shaft, has an opening in its bottom, and is arranged to operate with a scraper in such a manner that the flour or other substance to be bolted or screened will be fed properly to the screens.

To enable those skilled in the art to fully understand and construct my invention, I will proceed to describe it.

A represents a vertical shaft, the upper end of which has its bearing in a cross-piece, a , at the upper ends of two uprights, $b b$, which are attached to a suitable base, B. The lower end of the shaft A is stepped in a block, C, which is attached to the base B. The hole c in the block C is of oblong form, as shown in Fig. 3 and in dotted lines in Fig. 2, so as to admit of a lateral movement of the lower journal, d , of the shaft A, which journal works in said hole, and the upper surface of the block C is provided with two vertical projections, $e e$, one at each end of the hole c , as shown clearly in Fig. 3. The upper surface of the block C, at each side of the hole c , is made of inclined form, as

shown at ff' , one inclined surface being in a reverse position to the other. The shaft A is of polygonal form, and it has a series of arms, g , attached to it in two spiral lines, and upon these arms the screen D' and chute D are secured. The screen may be constructed of wire-cloth, or bolting-cloth may be used, according to the work designed to be done. For bolting indian-meal a wire-screen may be used, but bolting-cloth would be preferable for bolting flour and dusting bran. The chute D may be constructed of canvas or thin boards. The screen D' is directly over the chute D, and they both are inclosed within a case, E, which may extend from the top to the bottom of the shaft A, so as to completely enclose them; or it may be so constructed as simply to form a guard at the outer edges of the screen and chute to prevent the substance being bolted or screened from passing off of the edges of the screen and chute. The screen or chute may extend one or more times around the shaft A, and they have a slightly-inclined position, being higher at their outer than at their inner edges, as shown clearly in Fig. 1. The object of this will be presently explained. On the shaft A, above the screen D', there is placed a circular hopper, F, which has a slot or opening, h , made radially in its bottom and extending from the shaft A to the outer edge of the bottom. The hopper E is equal in diameter to the case E, and the upper edge of the former is directly underneath the cross-piece a of the uprights $b b$. To the cross-piece a there is attached at one side a scraper, G, which extends down within the hopper and has its lower edge nearly in contact with the bottom of the hopper, as shown in Fig. 1. To the base B there is attached a circular box, H, which is divided by a partition, i , so as to form two annular concentric troughs, I I', each of which has a discharge-opening, j , in its bottom, as indicated by the dotted lines in Fig. 2, and to the lower end of the screen D' there is attached a spout, J', which conveys the bran into the trough I', the other spout, J, being attached to the chute D, and conveying the flour into the trough I.

The operation is as follows: The flour or other substance to be bolted is placed in the hopper F, and a rotary motion is given the shaft A by any convenient power. The flour or other substance in the hopper G is, as said hopper rotates, discharged through the open-

ing *h* by means of the scraper *G*. The flour falls upon the screen *D'* and passes through it down upon the chute *D*, the bran being retained on the screen *D'* and discharged therefrom through spout *J'* into the trough *I'*, while the flour is discharged from the chute *D* through the spout *J* into the trough *I*. As the shaft *A* rotates it has an up-and-down and a lateral shake motion communicated to it in consequence of a projection, *k*, on the lower journal, *d*, of the shaft acting upon the inclined surfaces *f f'* of the block *C*, and against the vertical projections *e e* thereon. This projection *k* raises the shaft in passing over the inclined surfaces *f f'*, and as said projection reaches the upper part of each inclined surface it comes in contact with a vertical projection, *e*, and throws the journal *d* back in the hole *c*, which gives a lateral movement to the shaft *A*, and as soon as the projection *k* clears the projection *e*, with which it came in contact, it drops upon the lower end of the inclined surface *f f'* in front of it and again raises the shaft and the parts attached to it until it comes in contact with the other projection, *e*, when the lateral movement is again given the shaft until the projection *k* clears the projection *e* and the former falls upon the inclined surface in front of it. Thus an up-and-down and lateral shake motion is given the screen and chute, and the former prevented from becoming choked or clogged.

The device occupies but little space, and may be constructed at a very reasonable cost. The screen and chute have an inclined position given them, being elevated at their outer ends in order to counteract centrifugal force and prevent the flour and grain being thrown in contact with the case *E*.

Having thus described my invention, what I claim as new, and desire to secure by Letters Patent, is—

1. The spiral screen *D'*, one or more, attached to a vertical rotating shaft, *A*, in connection with a spiral chute, *D*, also attached to the shaft *A*, the screen and chute being encompassed by a case, *E*, and all arranged to operate as and for the purpose herein set forth.
2. The hopper *F*, attached to the shaft *A* above the screen *D*, in combination with the stationary scraper *G* and the opening *h* in the bottom of the hopper, for the purpose herein set forth.
3. The annular troughs *I I* on the base *B*, and underneath the screen *D'* and chute *D*, when used in connection with the screen and chute arranged on the shaft *A* and the spouts *J J'*, for the purpose specified.

J. WRIGHT.
